(57) **CLAIM**

The ornamental design for a suspender hook, as shown and described.

DESCRIPTION

FIG. 1 is a rear perspective view of a suspender hook showing my new design;

FIG. 2 is a front perspective view thereof;

FIG. 3 is rear view thereof;

FIG. 4 is a front view thereof;

FIG. 5 is a top view thereof;

FIG. 6 is a bottom view thereof;

FIG. 7 is a right side view thereof;

FIG. 8 is a left side view thereof; and,

FIG. 9 is a rear view thereof, shown in a position of use with a suspender.

The broken lines shown in the drawings depict environment that forms no part of the claimed design.

1 Claim, 4 Drawing Sheets
